DESIGN FOR A TERMINAL BLOCK FOR ELECTRICAL CONNECTIONS

Eugene R. Kulka, Mount Vernon, N. Y.

Application September 1, 1943, Serial No. 111,034

Term of patent 7 years

To all whom it may concern:

Be it known that I, Eugene R. Kulka, a citizen of the United States, residing at Mt. Vernon, in the county of Westchester and State of New York, have invented a new, original, and ornamental Design for a Terminal Block for Electrical Connections, of which the following is a specification, reference being had to the accompanying drawing, forming part thereof.

In the drawing

Fig. 1 is a top plan view of a terminal block for electrical connections showing my new design;

Fig. 2 is a side elevation thereof;

Fig. 3 is a bottom plan view;

Fig. 4 is an end elevation.

I claim:

The ornamental design for a terminal block for electrical connections, substantially as shown.

EUGENE R. KULKA.
